Dec. 143

Asa C. Brownell Boston Mass.
Letters patent (Design 143) Dated 14th August 1847

The schedule referred to in these Letters Patent and making part of the same

To all persons to whom these presents shall come: Be it known that I, Asa C. Brownell of Boston in the County of Suffolk and State of Massachusetts have invented a new and useful design for the side, or end, or door of a stove, and I do hereby declare that the same is fully described and represented in the following specification, and accompanying drawings, letters, figures, and references thereto.

Of said drawings, Figure 1 represents an elevation of my design. Figure 2, is a horizontal and longitudinal section of it. Figures 3. and 4 are sections on A.B and E.F of Figure 1. The said design consists of one or more gothic or pointed arched mouldings A. B. C. enclosed in a panel D' by a surrounding moulding E' in relief, a section of which as well as that of the gothic arches is exhibited in Figure 2.

What I claim as my invention in the said design is the combination of one or more of said pointed arches in alto relief with a sunken panel D', and circumscribing moulding E' as exhibited in the drawings.

In testimony whereof I have hereunto set my signature this twenty sixth day of June A.D. 1847.

Witnesses:
